UNITED STATES PATENT OFFICE

JAMES C. DAWSON, OF WEBSTER GROVES, MISSOURI, ASSIGNOR TO ELMA N. DAWSON,
OF WEBSTER GROVES, MISSOURI

LOOSE LEAF POST BINDER

Application filed June 27, 1930. Serial No. 464,230.

This invention relates to loose leaf binders and particularly to an improved method of hinging covers to the tubular binder bars.

The objects of the present invention are to secure stronger hinge members, less expensive parts, and more expeditious assembly than has previously proved possible.

These and other objects of the invention will become apparent from the specification and the appended drawings in which

Fig. 1 represents a perspective view of the assembled post binder;

Fig. 2 is a horizontal mid-section through one of the binder bars, the hinge and cover;

Fig. 3 illustrates in perspective my improved form of solid hinge plug;

Fig. 4 illustrates in perspective the improved form of perforated hinge plugs; and

Fig. 5 is a vertical section through one of the binder bars and a portion of the cover, taken on the line 5—5 of Fig. 2.

With reference to Fig. 1, the binder, generally indicated by 10, is composed of covers 11, 11, made from any suitable material 25 to which are affixed by rivets or otherwise a metallic tubular hinge member 12. The hinge pins 13, 13, Fig. 2, provided with an integral collar 14 and a pintle portion 15, are driven into the tubular hinge member 12 until the collar 14 is seated against the ends thereof.

The lower binder bar 16 (Fig. 1) is provided with two or more posts 17, 17 which project upwardly. The upper binder bar 18 35 is provided with holes 19 to cooperate with the posts, and, inside of the bar 18, a locking member 21 is slidably held by the screw 22 engaging in the abutment 23 in such a manner that the locking member may be forced out of line with the holes 19 and thus jam the posts. The screw 22 terminates in a squared head which may be turned by a key or small socket wrench indicated by 24.

The hinge plugs which I prefer to make 45 from wrought metal by a process which forms no part of the present invention, are then inserted in the end of the binder bar. The plugs are provided with a head portion 25 which presents a finished surface. The plug portion 26 fits the interior of the binder bars

16 and 18 closely. The pintle socket portion 27 is provided with an axial bore 28 and a coaxial counterbore 29.

Upon assembly, the plugs are driven into the ends of the binder bars. The pintle 15 55 is journaled in the bore 28 and the collar 14 is given clearance by the counterbore 29. Rivets 31 are set through the binder bars 16 and 18 and the transverse holes 32 in the plugs and hold the parts in assembly. In 60 order to give clearance to the key 24, one of the plugs is pierced through both the head and plug portions, as shown at 33, Fig. 4. The screw 22 projects slightly into the bore thus formed, as indicated in Fig. 2. 65

Since the wrought metal which I prefer to use for the plugs has much greater strength than the metals formerly used, it will be noticed that the assembly is greatly simplified and no reinforcing members are necessary to prevent the plug cracking between the plug portion and the pintle socket which has previously been an annoying difficulty. 70

What I claim is:

1. In a loose leaf binder, a tubular binder bar, a hinge plug closing the end of the bar having a plug portion, a pintle socket portion, and a head portion, the pintle socket portion being provided with two concentric bores, and the head and plug portions having 75 a bore extending through both of same, and a transverse bore extending through the plug portion, a cover member having a tubular margin, a pin engaging the tubular margin journaled in the pintle socket, and means engaging the transverse bore of the plug member and the walls of the binder bar holding the parts in assembled relation. 80

2. In a loose leaf binder, a tubular binder bar, a hinge plug closing the end of the bar having a plug portion, a pintle socket portion, and a head portion, the pintle socket portion being provided with two concentric bores, and a transverse bore extending 85 through the plug portion, a cover member having a tubular margin, a pin engaging the tubular margin journaled in the pintle socket, and means engaging the transverse bore of the plug member and the walls of the binder bar holding the parts in assembled relation. 90

50 95 100

3. A loose leaf binder comprising a cover, a hinge member having a tubular portion attached to the cover, a tubular clamping bar, a hinge plug closing the end of the clamping bar having a head portion and plug portion and a pintle socket portion, the pintle socket portion being provided with a journal bore and a counterbore, a hinge pin in the tubular hinge member and journaled in the pintle socket, and means engaging the tubular clamping bar and the plug portion to maintain the parts in assembled position.
4. In a loose leaf binder, tubular binder bars having hinge plugs, each comprising a head portion, a plug portion and a pintle socket portion, said socket portion having a bore and a counterbore therein, a cover member provided with a tubular margin, said cover member being hinged to the binder bar by a hinge pin having an integral collar dividing the pin into pin and pintle portions, the pin portion occupying the tubular margin, the pintle portion occupying the bore and the counterbore in the pintle socket giving clearance to the collar.
5. In a loose leaf binder, a tubular binder bar, a cover having a hinge member terminating in a tubular margin, a hinge plug closing the end of the binder bar having a head portion provided with separate plug and pintle socket portions extending therefrom, the pintle socket being counterbored, a hinge pin affixed in the tubular hinge margin and journaled in the pintle socket portion, and having a collar fitting in the counterbore, and means securing the plug in the binder bar.
6. A loose leaf binder hinge plug having a head portion, a plug portion, and a pintle socket portion, the pintle socket portion being provided with two concentric bores, one of said bores being adapted to form a journal for a hinge pin.
7. A loose leaf binder hinge plug having a head portion, a plug portion, a pintle socket portion, the pintle socket portion being provided with two concentric bores, one of said bores being adapted to form a journal for a hinge pin, and a transverse bore extending through the plug portion.
8. A loose leaf binder hinge plug having a head portion, a plug portion, and a pintle socket portion, a bore extending through the head and plug portions, the pintle socket portion being provided with two concentric bores, one of said bores being adapted to form a journal for a hinge pin.

In testimony whereof I affix my signature.
JAMES C. DAWSON.
